UNITED STATES PATENT OFFICE.

HERMAN C. LITCHFIELD, OF WAUKEGAN, ILLINOIS.

DISPENSING APPARATUS.

1,416,219.

Specification of Letters Patent. Patented May 16, 1922.

Application filed May 28, 1920. Serial No. 335,016.

To all whom it may concern:

Be it known that I, HERMAN C. LITCHFIELD, a citizen of the United States, residing at Waukegan, in the county of Lake 5 and State of Illinois, have invented new and useful Improvements in Dispensing Apparatus, of which the following is a specification.

This invention relates to a dispensing apparatus and has for its primary object the construction of an apparatus of this character capable of dispensing various articles of various shapes, one at a time or in quantities depending upon the exact association 15 of the parts.

A feature of the invention is the novel construction of the receiving device so that the operation of certain parts will be automatical so that it is only necessary for the 20 operator to give attention to the removal of the article.

A feature of the invention is the novel manner of constructing the receiver and associating same with the catch so that 25 an article can be readily removed and the weight of the remaining articles properly supported.

With these and other objects in view the invention will be better understood from 30 the following detailed description taken in connection with the accompanying drawing wherein—

Fig. 1 is a diagrammatic view showing the receiver in position to receive an article.

Fig. 2 is a similar view showing the receiver forced to a position to allow the article to be removed.

Again referring to the drawing illustrating one construction of my invention in a diagrammatic manner the numeral 1 designates a tube of any required shape or size to accommodate the articles to be dispensed. This tube is provided with an offset portion 45 2 for the purpose hereinafter described, and has an open bottom 3 co-operating with my improved form of receiver 4. This receiver 4 in its simplest construction is of a shape to receive articles and has one wall 5 arranged at an inclination so that when the article is received it will be slightly laterally displaced so that my improved retaining device, hereinafter described, will properly operate. This receiver 4 may be supported 50 in a plurality of manners to have a vertical movement, but for the purpose of illustra-

tion I have shown the post 7 as connected to the receiver slidably mounted in any suitable support 6. A spring 8 acts to force the receiver into the tube to the position 60 illustrated in Fig. 1 so as to receive an article. My improved retaining device consists of a catch 9 pivoted in a manner to be forced by the spring 10 into engagement with a stack of articles, when an article is 65 about to be removed as clearly shown in Fig. 2. I wish to call attention to the fact that the inclination of the wall 5 and its co-operation with the catch is such that in return movement of the receiver the catch 70 will be automatically forced to its normal position to allow another article to gravitate into position within the receiver 4. From this construction it will be seen that it is only necessary for the operator to push the 75 receiver down and then remove the article as the operation of the other parts is automatic.

A feature of my invention is the construction and association of parts in such a manner that articles of various shapes and sizes may be accommodated in the tube without the necessity of limiting the construction of a tube to a particular design. In concluding my description I wish to call attention to the fact that the drawing illustrates my invention in a diagrammatic manner, therefore it is to be understood that the construction and association of parts may be accomplished in various other manners 80 and the association of the receiver with the tube changed in a plurality of manners and, therefore I do not desire to be limited in any manner except as set forth in the claims 85 hereunto appended.

Having thus described my invention what I claim is:

1. A dispensing apparatus comprising a tube supporting the articles to be dispensed, a receiver arranged at the lower end of the 100 tube and having inclined wall for slightly displacing an article with relation to the tube when received by the receiver, a spring arranged to force the receiver into its proper relation with the tube, and a catch arranged 105 to support the articles in the tube when an article is being removed by the receiver.

2. A dispensing apparatus comprising a tube supporting the articles to be dispensed, a receiver arranged at the lower end of the 110 tube and having inclined wall for slightly displacing an article with relation to the

- tube when received by the receiver, a spring arranged to force the receiver into its proper relation with the tube, and a catch arranged to support the articles in the tube when an article is being removed by the receiver, said inclined wall being arranged to automatically retract the catch when the spring has forced the receiver to a position to receive another article.
10. 3. In a dispensing apparatus, a tubular container having an offset portion, a receiver to receive articles from the tubular container and mounted for movement longitudinally of the tubular container to displace articles received from the container, means for preventing displacement of articles in said tubular container during removal of one article by the receiver, said receiver adapted to operate said means to permit release of an article from the container when the receiver has been returned to a receiving position.
15. 4. In a dispensing apparatus, a tubular container having an offset portion, a receiver to receive articles from the tubular container and mounted for movement longitudinally of the tubular container to displace articles received from the container, means for preventing displacement of articles in said tubular container during removal of one article by the receiver, said receiver adapted to operate said means to permit re-
- lease of an article from the container when the receiver has been returned to a receiving position, a rod for guiding movement of said receiver, and a spring about said rod and engaging said receiver to return it to a receiving position.
5. A dispensing apparatus comprising a tube supporting the articles to be dispensed, a receiver arranged at the lower end of the tube and movable in a direction longitudinally of the tube, said receiver provided with an inclined surface to displace the articles laterally of the tube when received by the receiver, and a catch arranged to support the articles in the tube when an article is being removed by the receiver.
6. A dispensing apparatus comprising a tube supporting the articles to be dispensed, a receiver arranged at the lower end of the tube and movable in a direction longitudinally of the tube, said receiver provided with an inclined surface to displace the articles laterally of the tube when received by the receiver, and a catch arranged to support the articles in the tube when an article is being removed by the receiver, a guide rod attached to said receiver, and a spring about said guide rod to return the receiver to a receiving position after removal of an article thereby.

In testimony whereof I affix my signature.
HERMAN C. LITCHFIELD.
